UNITED STATES PATENT OFFICE

OTTO W. DECHAU, OF ROCHESTER, NEW YORK, ASSIGNOR TO DESIGN MFG. CO. INC., A CORPORATION OF NEW YORK

DESIGN FOR AN OPTICAL FRAME

Application filed January 27, 1930. Serial No. 34,806. Term of patent 3½ years.

To all whom it may concern:

Be it known that I, OTTO W. DECHAU, a citizen of the United States, residing at Rochester, in the county of Monroe and State of New York, have invented a new, original, and ornamental Design for Optical Frames, of which the following is a specification, reference being had to the accompanying drawing, forming part thereof.

I claim:

The ornamental design for an optical frame, as shown.

In testimony whereof I affix my signature.

OTTO W. DECHAU.
